D. F. ASBURY

OPERATOR FOR THE MOVABLE PARTS OF RADIO TUNING UNITS

Filed Feb. 5, 1924

UNITED STATES PATENT OFFICE.

DORSEY F. ASBURY, OF WASHINGTON, DISTRICT OF COLUMBIA.

OPERATOR FOR THE MOVABLE PARTS OF RADIO TUNING UNITS.

Application filed February 5, 1924. Serial No. 690,795.

My invention relates to operators for the movable parts of radio tuning units, and my aim is to provide improvements in means for operating the movable parts of a plurality of tuning units simultaneously, and individually for the purposes set forth in my prior applications serially numbered 683,756; 687,080; 688,547 and 689,338, said improvements consisting primarily in providing an operating means that is simple in construction, easy to operate, neat in appearance, and that is compact and readily and easily applied to radio apparatus of present commercial types substantially without alteration to the latter.

My inventive idea is capable of embodiment in different mechanical structures, one of which is illustrated in the accompanying drawings, but it is to be understood that the structure herein shown is intended only as a disclosure of the essential features and novel characteristics of my invention in a preferred form, and that its scope is as defined in the appended claims.

In the drawings, wherein like characters of reference denote corresponding parts in the different views:—

Figure 1 is an elevation of a portion of a radio receiving set showing a plurality of tuning units and a preferred form of my improved operating means associated therewith;

Figure 2, a plan view of one of the yieldable supports for the operator;

Figure 3, a transverse section on the line 3—3 of Figure 1;

Figure 4, a transverse section on the line 4—4 of Figure 1; and

Figure 5, a view similar to Figure 4 showing a slight modification of my invention.

Referring now to the drawings in detail, it will be observed that I have illustrated in part a radio apparatus of well known commercial type including a base board 10 having mounted thereon by means of brackets 11 a plurality of tuning units 12, 13 and 14, which latter may be of any preferred type, but which are herein conveniently illustrated as variable plate condensers each including a stator *a* and a rotor *b*, as shown and described in my aforementioned applications 683,756; 687,080; 688,547 and 689,338. Said tuning units are arranged abreast and their movable parts, rotors *b*, are provided, respectively, with dials or disks

15, 16 and 17 by means of which they may be adjusted to cause them to tune with different wave lengths.

My improved means for adjusting the rotors *b* collectively and individually through the instrumentality of the dials or disks 15, 16 and 17 consists of an elongated rod 18 of preferably rectangular cross section supported from the base board 10 and slidably carrying a plurality of plates 19, 20 and 21 contacting respectively, with the peripheries of said dials or disks whereby they are simultaneously rotated when said bar is shifted longitudinally, and individually rotated by shifting the plates 19, 20 and 21 longitudinally with respect to said rod.

Preferably the rod 18 is yieldably supported to maintain the plates 19, 20 and 21 at all times in correct driving engagement with the peripheries of the dials or disks 15, 16 and 17, respectively, and to so support said rod I provide a plurality of duplicate devices each including a roller 22 centrally grooved parallel to and between its sides as indicated at 23 to provide a short shaft 24 adapted to be received within a U-shaped recess in an upstanding lug 25 at one end of an inherently resilient plate 26, the other end of which is secured to the base board 10, flanges 27 being provided on the roller to hold the rod 18 against lateral movement and to thus maintain the same aligned with the peripheries of the dials or disks 15, 16 and 17. The plates 26 are of such shape that they may be secured to the base board 10 by the same fasteners that are utilized to secure the supporting brackets 11 of the tuning units 12, 13 and 14 thereto, and since the brackets 11, plates 26, rollers 22 and the rod 18 are formed of metal, such parts serve to produce an electrical connection between the tuning units, which connection when grounded, as by means of the conductor 29, has been found by experiment to affect an apparatus in some unknown manner with the result that tuning thereof with certain wave lengths, ordinarily extremely difficult if not impossible of attainment, is, by such connection attained with ease.

The plates 19, 20 and 21 have frictional engagement with the rod 18, so that they are movable with said rod to rotate the dials or disks 15, 16 and 17 simultaneously when said rod is shifted. They may be in-

dividually shifted longitudinally with respect to said rod, however, to rotate individual dials or disks, and in order to so shift them, I mount on said rod transversely thereof by means of blocks 30, shafts 31, each carrying a pair of eccentric disks 32 operating, respectively, between pairs of down-turned fingers 33 on said plates. Thus, when a shaft 31 is rotated by means of a suitable knob or hand grip device 34, the eccentrics react from the rod 18 against one or the other of each pair of fingers 33 to shift the associated plate longitudinally with respect to said rod. The fingers 33 at one end of each plate and other down-turned fingers 35 at the other end thereof cooperate with the rod 18 to prevent lateral movement of the plates with respect to said rod.

As set forth in my prior application 683,756, it is desirable in some instances to cause the movable part of one or more tuning units to move at times at a different rate of speed with respect to the movable parts of other units when all of said movable parts are moved simultaneously, and to accomplish this purpose, I form one or more of the dials or disks of irregular outline and correspondingly shape the associated plate or plates 19, 20 or 21 so that driving contact is always maintained between such parts, for example, I chordally cut away a dial or disk as indicated at 36 and form the plate in association with such dial or disk with an offset portion 37 of such shape that it has rolling contact with the flat peripheral surface produced by said chordal, cut-away portion, and thus that particular dial or disk is caused to rotate, within the limits of its cut-away portion, at a different rate of speed from the other dials or disks, in which connection it will be observed that due to the present arrangement a correct relation of the irregular surfaces of the dials or disks with the companion surfaces of the associated plate or plates is maintained regardless of what simultaneous or individual adjustments are imparted to the dials or disks.

The modification shown in Figure 5 consists in forming roller 22' with flanges 27' of such depth that they extend slightly above the upper face of the rod 18 thereby to engage the sides of the plates 19, 20 and 21 that extend beyond the sides of the rod and thus hold said plates out of frictional contact with the rod, the purpose being to render the plates freely slideable, so as to necessitate only slight force being applied to the eccentrics for operating them. When the plates are thus supported, the means to cause them to move with the rod 18 when the latter is shifted will be included in the eccentric operating means, such means consisting for example of a friction washer

similar to that shown in association with the eccentric in my aforesaid application 683,756.

I claim:

1. In radio apparatus, a tuning unit a part of which is movable, an operator for moving said movable part bodily movable with respect thereto to secure rough adjustments thereof, means to hold said operator against movement, and vernier means carried by said operator and movable with respect thereto to move said movable part to secure minute adjustments thereof when the operator is held against movement.

2. In radio apparatus, a tuning unit a part of which is movable, a bodily movable operator for moving said movable part to secure rough adjustments thereof, means to hold said operator against movement, and a member carried by said operator bodily movable with respect thereto to move said movable part to secure minute adjustments thereof when the operator is held against movement.

3. In radio apparatus, a tuning unit a part of which is movable, an operator movable to move said movable part to secure rough adjustments thereof, and a member carried by said operator and partaking of movement in the same direction as the latter independently thereof to move said movable part to secure minute adjustments thereof.

4. In radio apparatus a tuning unit a part of which is movable, an operator longitudinally movable to move said movable part to secure rough adjustments thereof, and a member carried by said operator and movable longitudinally thereof to move said movable part to secure minute adjustments thereof.

5. In radio apparatus, a tuning unit a part of which is movable, an operator movable to move said movable part to secure rough adjustments thereof, and a member slideable on said operator to move said movable part to secure minute adjustments thereof.

6. In radio apparatus, a tuning unit a part of which is movable, an operator bodily movable with respect to said movable part to move the latter to secure rough adjustments thereof, a member carried by and movable with respect to said operator to move said movable part to secure minute adjustments thereof, and means reacting from said operator to move said member.

7. In radio apparatus, a plurality of tuning units a part each of which is movable, a single operator for moving the movable parts of a plurality of said tuning units collectively, and vernier means carried by said operator for moving said movable parts individually.

8. In radio apparatus, a tuning unit a part of which is movable, a bodily movable oper-

ator for moving said movable part, means to hold said operator against movement, a member slidable on said operator to move said movable part when said operator is held 5 against movement, fingers on said member cooperating with said operator to hold said member against lateral movement with respect thereto, and an eccentric carried by said operator and cooperating with said 10 fingers to slide said member.

9. In radio apparatus, a plurality of tuning units a part of each of which is movable, a rod common to a movable part of each unit for moving said parts collectively, a plurality 15 of plates one between said rod and each movable part, and means carried by said

rod for individually moving said plates thereby to individually move said movable parts.

10. In radio apparatus, a plurality of tuning units a part of each of which is movable, a rod common to a movable part of each unit for moving said parts collectively, a plurality of plates slidably mounted on said rod and operatively connected with said movable 25 parts, respectively, and rotatable means carried by said rod for sliding said plates individually with respect thereto thereby to individually move said movable parts.

In testimony whereof I hereunto affix my 30 signature.

DORSEY F. ASBURY.
